PHYSICIAN'S EXAMINING TABLE TOP

Joseph J. Lelugas, Two Rivers, Wis., assignor to American Hospital Supply Corporation, Evanston, Ill., a corporation of Illinois

Filed Aug. 29, 1969, Ser. No. 18,912

Term of patent 14 years

Int. Cl. D24—02; D6—02

U.S. Cl. D83—1

FIG. 1 is a top perspective view of a physician's examining table top, showing my new design;

FIG. 2 is a perspective view showing the other side and the head end of the table top shown in FIG. 1;

FIG. 3 is a perspective view similar to FIG. 1 but showing sections of the top in fully raised positions.

I claim:

The ornamental design for a physician's examining table top, substantially as shown and described.
